UNITED STATES PATENT OFFICE.

ARTUR DRAUDEN, OF BROOKLYN, NEW YORK.

TOY WHIRLIGIG.

Application filed June 15, 1927. Serial No. 198,888.

The main object of this invention is the provision of a toy and amusement device of novel construction. The device may be provided in miniature as a toy with or without 5 mechanical actuating means, and as an amusement device for carrying passengers with appropriate driving means.

Another object is to provide such a toy with novel means of construction whereby 10 the device, once set in motion, will continue in motion for a relatively long period of time.

Another object is the provision of a novel bearing between the pedestal supporting the 15 device and the moving part of the device.

The above and other objects will become apparent in the description below, in which characters of reference refer to like-named parts in the drawings.

20 Referring briefly to the drawings, Fig. 1 is an elevational view of the device.

Fig. 2 is a plan view of the device.

Fig. 3 is an enlarged central sectional view through the upper neck of the supporting pedestal.

25 Referring in detail to the drawings, the numeral 10 indicates the supporting pedestal of the device, narrowing upwardly into a neck 11. A peg 12, supported dependently from a drum-shaped anchor 13, is supported loosely in the top of the neck 11. Spaced-apart angular rods 14 extend downward and outward from the lower part of the anchor 13, and have their lower ends imbedded in an annular weight 15, which 30 they support, this weight providing a balance for the device in action.

Other angular rods 16 extend upward and outward from the anchor 13, and support in 40 pivotal suspension, miniature airplane models 17.

The upper end of the neck 11 of the pedestal is cupped out to provide a recess. On opposite sides of the recess horizontal 45 ears 18 are provided over the recess, in diametrically opposed relation. Vertical pins 19 are mounted rigidly between the ears 18 and the floor of the recess, and each pin has a small ball 20 rotatably mounted thereon.

50 A larger ball 21, having an equatorial

groove 22 thereon, is loosely mounted between the balls 20, the latter registering in the groove 22 and thereby preventing the ball 21 from any movement excepting rotation in a horizontal plane. A conical cut-out portion is provided in the ball 21 to seat the peg 12.

When used as a toy, the device may be used as shown or it may be provided with 55 mechanical actuating means such as spring 60 motors for the propellers in the airplanes. Once the device has been set in motion, the entire portion supported by the peg 12 will 65 rotate about its center, and at the same time it will have a wobbling motion caused by the balance weight 15. The planes will thus rise and dip rhythmically while rotating about the pedestal. To accommodate the sidewise motion of the peg, the cut-out 23 is made of a slightly greater angle of taper 70 than that of the peg 12.

The bearing shown in Fig. 3 greatly diminishes the friction between the moving and stationary parts of the device, and therefore the planes will continue to revolve 75 for a relatively long time. First, the peg is free to revolve in the cut-out 23; the ball 21 is free to revolve between the balls 20 on the base of the recess; and the balls 20 are free to revolve upon their shafts 19. 80

When used as an amusement device to carry passengers, actuating means of various kinds may be employed, such as individually actuated propellers on the planes, or means for giving the moving part one or 85 more rapid turns and then releasing it to rotate by its momentum until brought to rest.

The device may also be used for various commercial purposes such as for advertising 90 and on aeroplane landing devices.

What is claimed is as follows:

1. A device of the class described comprising a pedestal, a recess in the upper end of said pedestal, a ball loosely mounted in 95 said recess, means for guiding said ball to rotation in a horizontal plane, said ball having a cut-out portion, a peg loosely supported in said cut-out portion, an anchor rigid with the upper end of said peg, sup- 100

porting means extending from said anchor, and miniature models attached to said supporting means.

2. A device of the class described comprising a pedestal, said pedestal having a recess in its upper end, a ball loosely mounted in said recess, a circumferential horizontal groove in said ball, additional

balls rotatably supported in said recess and registering in said groove, said first-named ball having a cut-out portion, a peg loosely supported in said cut-out portion, and outwardly extending supports carried by said peg. 10

In testimony whereof I affix my signature.
ARTUR DRAUDEN.
